DESIGN FOR AN ELECTRIC SOLDERING IRON

Arthur L. Johnson, Roselle Park, N. J.

Application July 7, 1942, Serial No. 107,445

Term of patent 14 years

To all whom it may concern:

Be it known that I, Arthur L. Johnson, a citizen of the United States, residing at Roselle Park, in the county of Union and State of New Jersey, have invented a new, original, and ornamental Design for an Electric Soldering Iron, of which the following is a specification, reference being had to the accompanying drawing, forming a part thereof,

In said drawing, Figure 1 is a side elevational, and Figure 2 is an end elevational view of an electric soldering iron embodying my new design.

I claim:

The ornamental design for an electric soldering iron, as shown.

ARTHUR L. JOHNSON.
